CLAIM

The ornamental design for a magnifier, as shown and described.

DESCRIPTION

FIG. 1 is a perspective view of a magnifier showing our new design;

FIG. 2 is another perspective view of the magnifier shown in FIG. 1;

FIG. 3 is a front elevational view of the magnifier shown in FIG. 1;

FIG. 4 is a rear elevational view of the magnifier shown in FIG. 1;

FIG. 5 is a right side elevational view of the magnifier shown in FIG. 1;

FIG. 6 is a left side elevational view of the magnifier shown in FIG. 1;

FIG. 7 is a top plan view of the magnifier shown in FIG. 1;

FIG. 8 is a bottom plan view of the magnifier shown in FIG. 1;

FIG. 9 is a perspective view of the magnifier shown in FIG. 1, wherein the magnifier is shown in a stowed position;

FIG. 10 is another perspective view of the magnifier shown in FIG. 9;

FIG. 11 is a front elevational view of the magnifier shown in FIG. 9;

FIG. 12 is a rear elevational view of the magnifier shown in FIG. 9;

FIG. 13 is a right side elevational view of the magnifier shown in FIG. 9;

FIG. 14 is a left side elevational view of the magnifier shown in FIG. 9;

FIG. 15 is a top plan view of the magnifier shown in FIG. 9; and,

FIG. 16 is a bottom plan view of the magnifier shown in FIG. 9.

(Continued)

The evenly spaced broken lines shown in the figures illustrate portions of the magnifier that form no part of the claimed design.
